UNITED STATES PATENT OFFICE.

TRUMAN G. PADDACK, OF WYOMING, OHIO, ASSIGNOR TO THE STEARNS AND FOSTER COMPANY, OF LOCKLAND, OHIO, A CORPORATION OF OHIO.

UPHOLSTERING MACHINE.

Application filed October 19, 1923. Serial No. 669,626.

To all whom it may concern:

Be it known that I, TRUMAN G. PADDACK, a citizen of the United States, and a resident of Wyoming, in the county of Hamilton and State of Ohio, have invented certain new and useful Improvements in Upholstering Machines, of which the following is a full, clear, and exact description, reference being had to the accompanying drawings, forming part of this specification.

The object of my invention is to provide an apparatus for packing the pockets of upholstery goods with soft material such as cotton batting, and the like, which is usually employed to provide a soft cushion for the goods.

It is quite a difficult task to fill the pockets effectively by reason of the friction of the packing on the side walls of the pockets which tends to cause uneven spots and lack of uniform distribution. This is particularly noticeable where strips of cotton batting are employed, which are usually furnished in a roll, which have to be pulled through the pockets.

It is the purpose, therefore, of my invention to provide an apparatus in which these difficulties in handling the strips are avoided, and the strips may be inserted in the pockets uniformly and evenly.

The invention consists of that novel construction of funnel for filling the pleats and pockets and method of operation to be hereinafter particularly pointed out and claimed, whereby this result may be attained.

In the drawings:

Figure 1 is a side elevation of my machine.

Figure 2 is a plan view of the machine with the funnel carrying the packing in the pocket to be filled.

Figure 3 is a similar view with the pocket withdrawn.

Figure 4 is a cross section of the machine taken through the funnel.

A table 1 is provided about twice the length of the upholstery goods to be stuffed, and preferably of a width slightly greater than the width of one of the pockets to be filled, and also preferably with a sheet metal top surface, rounded off at the sides to provide aprons 2, 2. Mounted on this table lengthwise at one end is a trough or channel of sheet metal 3, raised slightly from the table surface to leave a space to permit of

the goods being passed thereunder. This trough has incurved longitudinal side edges 4, 4, under which edges a cover plate 5 fits. The cover is substantially double the length of the body of the trough, and is provided with a handle 6 for convenience in sliding the cover back and forth for the purpose to be described. The trough with its cover thus forms a funnel which is of the cross sectional shape of the filled pocket of the upholstery goods. The upholstery 7 is furnished in lengths of the desired width and with the pockets 8 formed with the desired backing, and the goods is passed over the table in front of the funnel. Before the machine is ready for use, the funnel body is first loaded with the strip of cotton batting, or other suitable filling material 9. This material is usually folded in bellows folds or comes in rolls and the roll is mounted in a receptacle 10 at the end of the table. To load the machine the cover 5 is slipped completely off of the trough which leaves it open on top, and the strip of batting 9 is threaded into the trough by holding the tip end of the batting over the end of the cover 5 and then sliding the cover back into the trough 3, so that the trough 3 and cover 5 form a complete funnel filled with batting 9. It will be understood that the strip of batting before it is placed in the funnel is fluffy and occupies a greater space than the section of the funnel, and that when located in the funnel, the strip is compressed as it is intended to be when filled into the pocket of the upholstery.

After the machine is loaded, one pocket in the upholstery is drawn on the loaded funnel, the operator grasps the cover 5, the strip 9 and the pocket 8 at the point where the cover and bat project through the pocket and all three parts are then moved in unison until the pocket is clear of the end of the trough 3. This movement at the same time draws a new supply of batting 9 into the trough 3 from the receptacle 10.

The operator then holds the end of the strip 9 and the pocket 8 while the cover plate is drawn out of the pocket back through the funnel trough to position shown in Figure 1, leaving the strip of batting 9 in the pocket. The batting strip is then severed at the end of the funnel nearest the pocket, the next pocket is pulled over the form, and the operator proceeds as before, the cover plate

being drawn with the upholstery as the pocket is drawn off the funnel, and then the cover is slid back to place. In this way the pockets can be filled uniformly and very rapidly, and the strain in the packing strip is reduced to a minimum. The movement of the cover plate prevents any undue friction as the strip of cotton batting is never pulled against the friction of the trough and cover 10 at the same time, and the cover plate goes with the strip as the pocket is pulled off the trough and serves as a backing for the strip. Then the batting strip in the pocket permits the cover to be returned to its normal position without disturbing the conformation.

I have illustrated the principles of my invention with a single funnel, but any number of funnels might be mounted side by side, and a plurality of pockets filled simultaneously. Also instead of pulling the goods upon a fixed trough, the funnel could be arranged to be inserted into the pocket and the top cover held with the packing as the trough is withdrawn. The essential feature 25 of my invention resides in the open trough or funnel with the sliding cover.

Having thus described my invention, what I claim as new and desire to secure by Letters Patent, is:—

30 1. In a device of the character specified, a fixedly held funnel open at both ends for the reception and delivery of the material for packing the pockets of upholstery goods, said funnel having at least one longitudinal section, slideable on the fixedly held portion to enter the pocket with the packing material and to be withdrawn therefrom separately.

2. In a device of the character specified, a fixedly held funnel open at both ends for 40 the reception and delivery of the material for packing the pockets of upholstery goods, said funnel constructed of a body portion for the bottom and sides and a slidable top cover, adapted to be drawn as a unit into 45 the pocket and withdrawn therefrom separately.

3. In a device of the character specified, a table, with a funnel secured thereto, with the body of the funnel raised from the table 50 surface to permit the pockets in the goods to be upholstered to be drawn thereon, the funnel provided with a sliding top portion, adapted to be drawn into the pocket of the goods and to be drawn therefrom separately. 55

4. In a device of the character specified, a table, with a receptacle at one end for a roll of a narrow strip of filling material, a funnel mounted on the table to receive the strip as drawn from the roll, the body of the 60 funnel raised from the surface of the table to permit the pockets to be drawn thereon, and a slidable top cover for the funnel, adapted to be slid out of the funnel body into the pockets for the strip and withdrawn 65 therefrom separately, the top cover being substantially twice the length of the body of the funnel.

5. A machine for stuffing upholstery which comprises a funnel shaped to receive 70 an upholstery pocket, said funnel having a separate longitudinal section held against lateral displacement but slideable upon the funnel, said slideable section being provided with a handle.
